UNITED STATES PATENT OFFICE.

GEORGE K. JESSUP, OF NEW YORK, N. Y., ASSIGNOR TO THOMAS E. MURRAY, OF NEW YORK, N. Y.

SEAL-FASTENING.

1,055,638.

Specification of Letters Patent. Patented Mar. 11, 1913.

Application filed August 8, 1912. Serial No. 714,007.

To all whom it may concern:

Be it known that I, GEORGE K. JESSUP, a citizen of the United States, residing at New York, in the county of New York and State 5 of New York, have invented a certain new and useful Improvement in Seal-Fastenings, of which the following is a specification.

The invention relates to a seal fastening, of the type comprising a casing and a 10 shackle having arms entering said casing; and consists in the construction, hereinafter set forth, whereby the shackle after insertion becomes locked in said casing so that it cannot be removed without mutilation of the 15 device and consequent revelation of tampering therewith.

In the accompanying drawings—Figure 1 is a sectional view of my seal fastening, showing the parts in position for engagement. Fig. 2 is a similar view, showing the 20 parts engaged. Fig. 3 shows the plate F separately and in perspective. Fig. 4 is a sectional view of the parts engaged, on the line x, x of Fig. 2. Fig. 5 shows the body 25 portion and Fig. 6 the cover of the casing separately and in perspective.

Similar letters of reference indicate like parts.

The casing, preferably of metal, comprises 30 the flanged cover A and body piece B, Fig. 5. The cover A receives the body piece B, and is provided with holes C for the reception of the shackle D, said holes registering with notches E in body piece B, when said 35 parts are put together, as hereinafter explained. F, Fig. 3, is a disk-shaped plate, also preferably of metal, of suitable size to fit snugly in body piece B of the casing. Said plate F has four slits made in it, as 40 shown in Fig. 3, so that portions of it may be bent outwardly to produce partitions G, H, I, J, forming two channels. Near the lower ends of the partitions are openings K, and above said openings on the outer sides 45 of the partitions depressions or grooves L are made. Within the casing are two loose springs M and N, of wire and in loop form, each having at its middle portion a turn O. In each arm of the shackle D is an opening P.

In assembling the device, the plate F is placed in the body piece B of the casing, and the ends of the springs M, N are inserted in the upper portions of the grooves L, as 55 shown in Fig. 1. The cover A is then ap-

plied to the body piece B, and the edge of the flange of said cover is knurled or rolled over body piece B, thus securing said parts together. The shackle D is then inserted through the holes C and notches E into the 60 channels formed by the partitions G, H, I, J, and is pushed downwardly in said channels so that its extremities strike the springs M, N and carry them downward, the ends of the springs sliding in grooves L, until said 65 ends enter the holes K in said partitions and also the holes P in the arms of the shackle and overlap one another, as shown at Q, thus acting as latches to lock said shackle in place, as shown in Fig. 2.

It will be apparent that after engagement as described, the springs M, N lock the shackle to the plate F, while the shackle itself by its passage through the holes C locks said plate to the cover A of the casing. 70 The cover and body piece cannot be separated without mutilating the knurling, which of itself reveals any tampering with the device. Furthermore, the openings R in the plate made by bending outwardly the partitions G, H, I, J, are to be of such width as that, after cover A is removed, any tool inserted in the springs M, N and operated to separate the overlapping ends thereof, cannot do so sufficiently to remove said ends 85 from the holes in the shackles, because of said tool striking the outer edges of said openings.

I claim:

1. A seal fastening, comprising a casing having separated openings in its peripheral wall, a U-shaped shackle having an opening in each arm, partitions within said casing forming two separated channels receiving said shackle arms and having openings, and loose springs in loop form within said casing and normally engaging said partitions above the openings therein; whereby upon said springs being pushed forwardly by said shackle arms entering said channels, the extremities of said springs shall enter the openings in said partitions and shackle arms and lock said arms to said partitions.

2. A seal fastening, comprising a casing formed of two flanged portions secured one within the other and having openings in their flanges, a plate therein having on one side transverse partitions forming two channels, each of said partitions having an opening near its inner end, loose springs in loop 100

110

- form within said casing, and a shackle entering said channels through the openings in said casing flanges and having an opening in each arm: the said parts being constructed and arranged so that said springs may be placed across the inner ends of said channels with their separated extremities resiliently engaging the outer sides of said partitions above the openings in said partitions, and upon said springs being pushed forwardly by said shackle passing through said channels, said extremities shall enter the openings in said partitions and said shackle arms and lock said shackle to said partitions.
- 15 3. A seal fastening, comprising a casing, a plate therein having on one side integral partitions produced by suitably cutting and bending said plate and forming two channels, each of said partitions having an opening near its inner end, loose springs in loop

form within said casing, and a shackle entering said channels through the openings in said casing flanges and having an opening in each arm: the said parts being constructed and arranged so that said springs may be placed across the inner ends of said channels with their separated extremities resiliently engaging the outer sides of said partitions above the openings in said partitions, and upon said springs being pushed forwardly by said shackle passing through said channels, said extremities shall enter the openings in said partitions and said shackle arms and lock said shackle to said partitions.

In testimony whereof I have affixed my signature in presence of two witnesses.

GEORGE K. JESSUP.
